US00D813724S

(12) **United States Design Patent** (10) **Patent No.:** **US D813,724 S**
(45) **Date of Patent:** **** Mar. 27, 2018**

(54) **UNMANNED AERIAL VEHICLE**

(71) Applicant: **SHENZHEN C-FLY INTELLIGENT TECHNOLOGY CO., LTD.**,
Shenzhen, Guangdong Province (CN)

(72) Inventor: **Guoqiang Hu**, Huarong County (CN)

(73) Assignee: **SHENZHEN C-FLY INTELLIGENT TECHNOLOGY CO., LTD.**,
Shenzhen, Guangdong Province (CN)

(**) Term: **15 Years**

(21) Appl. No.: **29/604,643**

(22) Filed: **May 18, 2017**

(51) **LOC (11) Cl.** **12-07**

(52) **U.S. Cl.**

USPC **D12/16.1**

(58) **Field of Classification Search**

USPC D12/16.1, 319, 325, 326, 327, 328,
D12/329-345; D21/436, 441, 442, 443,

(57) **CLAIM**

The ornamental design for an “unmanned aerial vehicle,” as shown and described.

DESCRIPTION

FIG. 1 is a perspective view of an unmanned aerial vehicle showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view viewed from another visual angle thereof;

FIG. 9 is a perspective view with the folded up wings viewed from another visual angle thereof; and,

FIG. 10 is another perspective view of FIG. 9.

1 Claim, 10 Drawing Sheets
